UNITED STATES PATENT OFFICE

GEORGE E. BALL, OF CRANSTON, RHODE ISLAND, ASSIGNOR TO THE AMERICAN THERMOS
BOTTLE COMPANY, OF NORWICH, CONNECTICUT, A CORPORATION OF OHIO

DESIGN FOR A JUG

Application filed June 14, 1932. Serial No. 44,077. Term of patent 14 years.

To all whom it may concern:

Be it known that I, GEORGE E. BALL, a citizen of the United States, residing at Cranston, Rhode Island, in the county of Providence and State of Rhode Island, have invented a new, original, and ornamental Design for Jugs, of which the following is a specification, reference being had to the ac-

companying drawing, forming part thereof.

Fig. 1 is a side view, and

Fig. 2 a plan view of a jug showing my new design.

I claim:

The ornamental design for a jug, as shown.

GEORGE E. BALL.
